UNITED STATES PATENT OFFICE.

HENRY C. BROWN, OF WOODBURY, NEW JERSEY.

CASE FOR HOLDING TALKING-MACHINE RECORDS.

956,516.

Specification of Letters Patent.

Patented May 3, 1910.

Application filed February 19, 1909. Serial No. 478,816.

To all whom it may concern:

Be it known that I, HENRY C. BROWN, a citizen of the United States, residing at Woodbury, in the county of Gloucester and

5 State of New Jersey, have invented certain Improvements in Cases for Holding Talking-Machine Records.

My invention relates to cases or portfolios for holding flat talking machine records. 10 Its leading purpose is to provide a simple, expandable construction having independently movable partitions, with means for controlling their movements and holding the records between them.

15 In the accompanying drawings, Figure 1 is a perspective view of a portfolio embodying my improvements; Fig. 2 is a sectional view representing details of the construction; Fig. 3 is a side view representing the 20 improvements with a modified form of strap; Fig. 4 is an end elevation of the portfolio; and Fig. 5 is a side elevation partially in section representing the improvements with a second modified form of strap.

25 The portfolio, as shown in the drawings, has a casing comprising the flat base 1, the side 2 hinged to the base, the strut 3 hinged to the side 2, the side 4 hinged to the base, the cover 5 hinged to the side 4, the flap 6 overlapping the side 2, the button 7 on the side 2 for engaging the eyelet 8 in the flap 6, and the handle 9 secured to the top 5. Partitions or division cards 10 stand upon the base 1 between the sides 2 and 4, and 35 through the bottoms and ends of the sides and partitions pass the sets of aligned apertures or eyelets 11 and 12. A strap 13 passes through the set of eyelets 11 and hooks 14 on the ends of the strap engage

40 keepers 15 fixed to the sides 2 and 4. Elastic straps 16 pass through the respective sets of eyelets 12, and hooks 17, similar to the hooks 14, engage keepers, similar to the keepers 15, fixed to the sides. A single strap 45 18 (Fig. 3) having ends thereof extending through the eyelets 12, to connections by hooks 14 with keepers 15, may be used to provide a greater length of elastic material and a greater range of expansion in opening 50 the case and separating the cards. The

ends of the straps passing through the eyelets may be provided with loops 19 and held by pins 20 therein (Fig. 5) in lieu of the hooks 14 and keepers 15.

The base 1 and top 5 may be omitted and 55 the portfolio or filing case thus adapted for expansion through an extended range, the capacity being readily alterable by altering the length of the straps and inserting or withdrawing partitions.

60 It will be understood that with the portfolio in the position shown in Fig. 1, the cards 10 can be separated for the insertion or withdrawal of flat articles, as the talking machine records 21 shown in Fig. 4. The 65 inelastic bottom strap and the elastic side straps, adapted to engage the peripheries of the disk shaped records, act to restore the sides to their normal position and draw together the movable parts of the case so that 70 pressure will be exerted on the faces of the disks to prevent them from warping, the straps guiding and holding the parts of the portfolio and its contents.

75 While it is my leading purpose to provide a case or portfolio in which flat talking machine records can be readily inserted, withdrawn and handled, it is to be understood that the construction is adapted and may be used for holding various other articles.

80 Having described my invention, I claim:

1. A case having a base, sides hinged thereto, independent partitions supported by said base and movable thereon between said sides, and fixed to said sides straps passing through the bottoms and ends of said partitions, said straps passing through the ends of said partitions being disposed in the median sections thereof.

85 2. An open ended case having a base, sides hinged to said base, a top hinged to one of said sides and having a flap adapted to engage the other of said sides, between said sides independent partitions having bottom and end eyelets extending therethrough, and 90 extending through said eyelets straps detachably connected to said sides.

95 3. The combination of a series of independent partitions, elastic straps connected with opposite edges of said partitions, mem- 100

bers exterior to said partitions and connected with said straps, said partitions being movable independently of said straps, and said straps acting to draw said members and partitions together to subject to pressure articles held between them.

5 In witness whereof I have hereunto set

my name this 18th day of February, 1909, in the presence of the subscribing witnesses.

HENRY C. BROWN.
